LIQUID DISTRIBUTOR FOR DIVIDING A CONSTANT OR VARIABLE STREAM OF LIQUID INTO TWO PARTIAL STREAMS

Jacques Beglinger, Basel, Switzerland, assignor to
J. R. Geigy A. G., Basel, Switzerland, a Swiss
company

Application August 1, 1949, Serial No. 107,944
In Switzerland August 6, 1948

2 Claims. (Cl. 137—166)

1

For technical purposes it is very often necessary to divide a stream of liquid (which itself can be varied at will) in a certain proportion (which, again, must be capable of variation). An example of this is afforded, in the case of a fractionating column, by the division of the condensate into a part which is collected and a part which is used for reflux i. e., by the regulation of the proportion of the reflux, this proportion being very important for the proper progress of the rectification.

In many cases this division is achieved by measuring the two parts of the stream with liquid metering instruments and then setting to the ratio required by adjusting stop-cocks or valves. This has the disadvantage, however, that the accuracy of the ratio is not guaranteed when the primary stream is altered and that, furthermore, calculation and rather delicate re-adjustments are necessary. This can be very tedious when continual changes in the ratio in which the liquid is split up are necessary.

In other cases the required distribution is brought about by allowing the primary stream to flow over a wier, dividing up the overflow width-wise in the required proportion and then leading off the two parts of the stream separately. This arrangement has the disadvantage of yielding inexact results when the primary stream is small or when extremes in the ratio of distribution occur (in the first case because of the small height of overflow with consequent extra sensitivity to variations from a horizontal position and in the second case because of the end contractions of the smaller part of the overflow).

In the following a distributor will be described which works on another principle and is designed to overcome the disadvantages of the systems mentioned above. This description is given with reference to the accompanying sheet of drawings, wherein:

Fig. 1 is a plan view of a relationship of parts according to the present invention;

Fig. 2a is an elevational view of a further relationship of parts incorporating the relationship according to Fig. 1;

Fig. 2b is a sectional view taken along line I—I of Fig. 2a;

Fig. 3a is a sectional view, taken along line III—III of Fig. 3b, of a complete apparatus according to this invention;

Fig. 3b is a sectional view taken along line II—II of Fig. 3a; and

Fig. 3c is a diagrammatic development of the section Fig. 3b along $2\pi r$.

2

The principle may be seen from Figures 1 (plan view) and 2a (elevation view).

The stream of liquid is led through one or several tubes 5 (see Fig. 1 plan view), which are arranged to rotate at a constant and moderate speed around a vertical axis, and then streams into a circular-cylindrical vessel 15 on a horizontal circular path with radius r . The stream is caught in two compartments formed by two radially arranged partitions of which one (3) is fixed and the other (4) can be rotatably adjusted about the vertical axis of the apparatus. The flow can thus be divided up in the ratio of the angles of arc α and $(2\pi - \alpha)$, i. e., in the ratio $\alpha : (2\pi - \alpha)$, and led off through the outlets 1 and 2. By turning the movable partition 4 the angular ratio can be adjusted to correspond with the ratio desired. Partition 3 is sealed off from the axis with pieces of leather or rubber strips, while partition 4 is similarly sealed off from the wall and bottom of the vessel 15 in order to make a clean separation between the compartments corresponding to the angles α and $(2\pi - \alpha)$.

In the case of liquids which are liable to cause trouble if such methods of sealing are employed, the angular sections α or $(2\pi - \alpha)$ can be divided off as shown diagrammatically in Figs. 2a (elevation view) and 2b (section through line I—I of Fig. 2a). For the production of the incoming stream rotating with moderate speed around the circumference $2\pi r$ the liquid to be divided up can suitably be led through the stationary tube 6 into a collector 19, which rotates about a vertical axis. One or more outlet tubes 5 are built into the vessel 19 so that the liquid flows into them as near to the axis as possible in order to minimize the effect of any slight tilting of the apparatus. These tubes, 5, lead radially outwards and pass downwards through the bottom of the vessel 19. They are constricted more or less in the form of jets at the outlet end so as to produce a smooth stream. The inlets to the tubes 5 are arranged at varying heights so that, according to the volume of flow, the first, then the second, next the third tube etc. come into action. This ensures that all the tubes 5, with the exception of the highest one which lies just at the liquid-level, discharge a full stream of liquid. This arrangement very largely eliminates any possibility of error due to discharge streams not running quite smoothly and regularly. At the same time it enables one and the same apparatus to be used for working with either small or large quantities of liquid. The quantity of the primary stream may vary through a range of 1:100 or

even more. The outlets 5 lead into the segment-adjuster 7 and the vessel 15 respectively. The contents of the segment-adjuster 7 flow through outlet 10 into the vessel 15 underneath, i. e. only in the area of outlet 2. The liquid intake of the area corresponding to the angle α flows out by the outlet 1, while the liquid intake of the area corresponding to the angle $2\pi - \alpha$ flows out by the outlet 2.

Figs. 3a, (section through line III—III of Fig. 3b), 3b, (section through line II—II of Fig. 3a) and 3c (development of the section along $2\pi r$), show sections of one form of the complete apparatus. 15 is the vessel with a cover 11 and an air outlet 18. The stream of liquid is led in through the tube 6. 19 is the rotating collector-vessel, driven by the motor 13. 20 is a device intended to ensure that the liquid level remains smooth during entry into the tubes 5. 7 is a movable segmental adjusting means, hereafter called a segment-adjuster by means of which the angle α or $(2\pi - \alpha)$ is divided off between the edges of the partition 8 and 7 itself. The liquid emerging from 7 at 10 can enter only into the area served by outlet 2, which is separated by the walls 8 and 9 from the other area of vessel 15, served by outlet 1. Wall 8 is sufficiently high to serve as a stop for the segment-adjuster 7. To permit full rotation of 7 within an angle of π (180°) a pocket 16 is formed in 8 at the level of outlet 10. The segment-adjuster 7 is made with a corresponding pocket 17. This arrangement permits adjustment to cover all out-flow ratios of outlet 1:outlet 2 from 0 to 1, i. e. of outlet 2: outlet 1 = 1 to ∞ . Thus, by fitting the exit tubes at 1 and 2 outside the apparatus with coupled stop-cocks any

desired continuous division of a liquid stream, on purely geometrical principles, can be achieved.

12 is an indicator which shows the desired out-flow ratios on the scale 14. 12 is attached to the shaft of the segment-adjuster 7.

What I claim is:

1. A liquid distributor comprising a rotatable cylindrical container incorporating at least two radial outlet tubes leading outwards and downwards, the inlet ends of the said tubes being arranged near the axis and at different heights, a cylindrical vessel mounted axially beneath said container, containing a fixed partition forming two completely separate semicircular compartments, with a semi-circular segment-adjuster movable angularly above said compartments, incorporating an outlet into one of the said compartments, and an outlet for every one of the said compartments.
- 15 2. In a liquid distributing system, a rotatable cylindrical container incorporating at least two radial outlet tubes leading outwards and downwards, the inlet ends of the said tubes being arranged near the axis of said container and at different heights.
